UNITED STATES PATENT OFFICE.

LEWIS L. SCOTT, OF ST. LOUIS, MISSOURI.

OIL-BURNER BOILER.

Application filed February 4, 1925. Serial No. 6,910.

This invention relates to improvements in hot water or steam boilers and particularly to boilers of that type provided with an oil burning equipment.

An object of the invention is to provide a boiler of compact arrangement while, at the same time, obtaining a maximum travel of the products of combustion along paths or channels where it will contact with the walls of the water containing portions of the boiler.

A further object is to secure a uniform heating of the water throughout the boiler, this being accomplished by the provision of a plurality of ducts through which uniform quantities of the products of combustion travel, means being provided for securing a uniform distribution of said products to the several ducts or flues, regardless of the varying distances between the several flues and the stack or discharge outlet for the products of combustion.

With these and other objects in view, the invention consists in certain novel details and combinations of parts, all as will hereinafter be more fully described and the novel features thereof particularly pointed out in the appended claims.

In the accompanying drawings,—
30 Figure 1 is a vertical sectional view of a boiler embodying the present improvements.

Fig. 2 is a transverse sectional view on the line 2—2 of Fig. 1.

35 Fig. 3 is a similar view on the line 3—3 of Fig. 1.

The present construction preferably embodies an oil burner for heating the water, this oil burner equipment comprising a motor 1 for operating a fuel pump 2 and a blower wheel that is enclosed in the casing 3. Fuel is brought from any source by the pump 2 through the pipe 4 and is discharged by said pump through a pipe 5 to the fuel spray nozzle 6 located within the boiler. Fuel sprayed from nozzle 6 is ignited by the spark plug 7 and air from the air blower 3 is conducted into the air receiver 8 where it is mixed with the fuel from nozzle 6. The nozzle and spark plug are located at the top of the boiler and the entire mixture after being ignited is conducted downwardly through a flame director 9 into the main portion of the combustion chamber 10 which is preferably cylindrical in cross section.

In the present instance the boiler com-

prises inner and outer shells 11, 20, the space between the two shells constituting the water space or boiler and the space within the inner shell 11 constituting the combustion chamber. The bottom portion of the boiler is formed by a base casting 17 having an air space therein above a water space 16, the partition between the air space and water space constituting the bottom wall of the combustion chamber 10. Water is supplied to the boiler through a pipe 26, in which there is a pressure control or reducing valve such as disclosed in prior U. S. Patent No. 1,353,844, the water being supplied from said pipe to the bottom water space 16 from whence it can flow to the water space 18 between the two shells by way of a series of supplies, such as indicated at 21. Preferably, the boiler is made up of three sections, the base section 17, an intermediate section, and a top section, the water space between the two shells in the two upper sections being substantially continuous by reason of the provision of a series of nipples 20 at the junction of the two upper sections. Steam or water is taken off from the upper end of the water space 18 through the outlet pipe 33 and the return pipe opening, indicated at 32, is located in the base section 17. With a structure as thus far described, the downward travel of the burning mixture along the inner shell 11 will result in raising the temperature of the water in space 18 to the temperature desired and it will be noted that the partially cooled gases will impinge upon the bottom of the combustion chamber and effect a rise in the temperature of the relatively cold, freshly supplied water in the base section.

To further guard against the loss of any of the heat units, however, there is provided a series of flues for carrying off the products of combustion, these flues extending upwardly from the air space in the base section through the water space 18 in the two upper sections. Each of said flues is located entirely within said water space 18 and is totally surrounded, throughout its length by water in said space, so that practically all the heat of the products of combustion is utilized in heating the water.

Preferably said flues are arranged around the boiler in pairs, there being three pairs 36, 36^a and 36^b in the present instance and the flues of each pair are connected to a stack or discharge opening 37 for the prod-

ucts of combustion. As the gases passing through the two flues 36^b farthest from stack 37 contact with a larger heat absorbing area and travel a longer and more tortuous path than those passing through flues 36 nearest said stack, it is apparent that in the absence of any regulating means there will be an uneven distribution of gases through the several sets of tube, larger quantities of 10 gases passing through flues 36 than through the others. For this reason, means are provided for securing a uniform distribution of the products of combustion flowing through the flues from the bottom of the combustion 15 chamber. While this might be accomplished in other ways, the preferred construction is to graduate the openings between the flues and stack, the flues 36 nearest the stack communicating therewith through a relatively 20 narrow opening 39 at the end of space 38 to which flues 36 connect; flues 36^b farthest from the stack communicating therewith through a relatively large opening 42 at the end of the space into which those flues 25 merge; and the intermediate flues 36^a communicating with said stack through a space 40 and opening 41 which is of a size substantially the mean of openings 39 and 42. This is the preferred arrangement where 30 three sets of flues are present but it will be understood that the openings through which the intermediate flues connect with the stack will be graduated in accordance with the number of flues used.

35 A boiler of this construction operates very efficiently but in instances where it is desired to provide hot water in the top of the boiler in a very short period of time, a water coil 12 is arranged in the combustion chamber 10. The coil is supported in chamber 10 by spacers such as 13 in order that the products of combustion will impinge against the wall of the water space as well as against the coil and the ends of said coil 40 are connected to the lower water chamber 16 as at 15 and to the upper end of the main water space as at 14.

45 As safety elements, the boiler is provided at its upper end with a gage 50 and at its lower end with a relief valve 29 by a pipe 30. This valve is connected by a pipe 31 to a sewer. In the base section there is also a small passageway or duct 35 through which unburned fuel is conducted to the exterior of the boiler. These last two elements 50 form no part of the present invention and need not be further described here. (They are fully described in my prior patent hereinbefore referred to.)

55 This arrangement, provides a boiler in which is embodied what is commonly known as the contra-flow principle, the greatest amount of heat being at the top of the combustion chamber 10 and after the gases are 60 gradually reduced in temperature during

their downward travel in said chamber they come in contact with the comparatively cold water supply in chamber 17, partially heating that water before it reaches the main portion of the combustion chamber walls. 70 The gases then pass through the flues within the main water space and additional heat extracted. Due to this contra-flow principle, the long travel of the products of combustion and their intimate contact with the 75 radiating surfaces confining the water, this boiler has very low stack temperatures and functions very efficiently.

What is claimed is:

1. In a boiler, the combination with a shell 80 having a combustion chamber therein, of a plurality of flues of different lengths communicating with said chamber and with a discharge outlet for the products of combustion, the openings of communication between the flues and said outlet being graduated in size according to the length of the flue, the opening of the shortest flue being smaller as compared with the opening from the longest flue. 85

2. In a boiler, the combination with a shell having a combustion chamber therein, of a plurality of flues of different lengths communicating with the lower end of said chamber and leading upwardly therefrom to a discharge outlet for the products of combustion, and openings of communication between the flues and said outlet being graduated in size according to the length of the flue, the opening from the shortest flue being smaller as compared with the opening from the longest flue, whereby the products of combustion from the combustion chamber are uniformly distributed to the several flues. 95

3. In a boiler, a combination with a shell having a combustion chamber therein, of a plurality of flues communicating with said chamber and with a discharge outlet for the products of combustion, said flues being of varying length, and means for governing the proportionate quantity or volume of products of combustion passing through the individual flues causing the said products of combustion to be uniformly distributed 110 through the several flues regardless of the differences in the length of the respective flues. 115

4. In a boiler, the combination with a shell having a combustion chamber therein, of a plurality of flues communicating with the lower end of said chamber and leading upwardly therefrom to a discharge outlet for the products of combustion, said flues being of different lengths, and means for determining the draft conditions in the individual flues to govern the proportionate volume of products of combustion passing through the individual flues whereby said products of combustion are uniformly distributed 120 125 130

through the several flues regardless of the differences in the length of the several flues.

5. In a boiler, the combination with a shell having a combustion chamber therein, of a plurality of flues of different lengths arranged in pairs around said chamber and communicating with the lower end thereof, each flue leading to a discharge outlet for the products of combustion, the opening between said outlet and the shortest pair of flues being comparatively narrow, the opening between said outlet and the longest pair of flues being comparatively large, and the opening between the outlet and the remaining pair of flues being substantially the mean of the width of the openings of the other pairs of flues.

6. A boiler comprising a combustion chamber, the wall of which constitutes a portion of the surface of a water circulating space surrounding the combustion chamber, a connection for supplying water to a water chamber in the bottom of the boiler, said chamber communicating with said water space and forming the bottom of the combustion chamber, an outlet connection at the top of said water space, means for initially directing the products of combustion downwardly in contact with the surface of the water space and the water chamber in the bottom of the combustion chamber, whereby the partially spent products of combustion will affect the relatively cold fresh supply of water in said bottom water chamber, a plurality of flues extending from the bottom of the combustion chamber upwardly through the water space to a discharge opening for the products of combustion, said flues being of varying lengths and the several flues having graduated outlets communicating with said discharge opening for uniformly discharging the products of combustion flowing from the bottom of the combustion chamber to the individual flues.

the combustion chamber upwardly through the water space to a discharge opening for the products of combustion, said flues being of varying lengths, and means for uniformly distributing the products of combustion from the bottom of the combustion chamber to the individual flues.

7. A boiler comprising a combustion chamber, the wall of which constitutes a portion of the surface of a water circulating space surrounding the combustion chamber, a connection for supplying water to a water chamber in the bottom of the boiler, said chamber communicating with said water space and forming the bottom of the combustion chamber, an outlet connection at the top of said water space, means for initially directing the products of combustion downwardly in contact with the surface of the water space and the water chamber in the bottom of the combustion chamber, whereby the partially spent products of combustion will affect the relatively cold fresh supply of water in said bottom water chamber, a plurality of flues extending from the bottom of the combustion chamber upwardly through the water space to a discharge opening for the products of combustion, said flues being of varying lengths and the several flues having graduated outlets communicating with said discharge opening for uniformly discharging the products of combustion flowing from the bottom of the combustion chamber to the individual flues.
